Filed Aug. 18, 1959, Ser. No. 834,477
5 Claims. (Cl. 110—8)

This invention relates to a refuse burning furnace or incinerator stoker. Such furnaces are used to burn market refuse, waste animal and vegetable matter and garbage and the like from municipalities, and industrially they are used to burn crates, boxes, paper and the like. It is an improvement on the furnace shown in the patent to Turner et al., No. 2,777,406 of January 15, 1957 and embodies the use of much of the structure shown therein. A single unit like that shown in the drawing of the present invention is adapted to destroy approximately three hundred tons of material in twenty-four hours. Furnaces for larger consumption would be side by side duplicates of the unit shown.

The objects of the present invention involve the development of a furnace of high capacity which operates continuously and in which the automatic mechanisms can be readily varied from centrally operating points, depending upon the nature of the material to be destroyed and the conditions of operation of the furnace at the time. Also the separate stages of the furnace may be individually controlled manually without affecting the setting of the automatic mechanisms. Also the operation of any one or more of the furnace stages or all the stages of the furnace could be stopped entirely without affecting the automatic system of control.

Other objects and advantages of the invention will be apparent from the following description and the accompanying drawings forming a part hereof and in which:

FIGURE 1 is a side elevational view of one unit of the furnace of this invention.

FIGURE 2 is a fragmentary side elevational view in greater detail showing two stages of the furnace bed and the drop-off or nose grate between them.

FIGURE 3 is a fragmentary horizontal sectional view of the grate bars and their mounting and driving connections.

FIGURE 4 is a fragmentary side elevation showing the top part of the control head and operating levers for manual operation and the cut-off for the fluid to the drive cylinders.

FIGURE 5 is a horizontal sectional view of the control head, showing the automatic control valves, taken on the line 5—5 of FIGURE 4.

FIGURE 6 is a vertical sectional view of the control head, taken on the line 6—6 of FIGURE 7.

FIGURE 7 is a vertical sectional view on line 7—7 of FIGURE 6.

FIGURE 8 is a vertical sectional view on line 8—8 of FIGURE 6.

FIGURE 9 is a fragmentary horizontal plan view of the control head with the top part removed.

FIGURE 10 is a vertical fragmentary sectional view on line 10—10 of FIGURE 7.

FIGURE 11 is a vertical longitudinal sectional view through the solenoid four-way valve which controls the automatic admission of fluid to the respective control lines.

FIGURE 12 is a diagrammatic view of the furnace grate bar drive cylinders and the means for operating them.

2

FIGURE 13 is a diagrammatic view of the cam sets on the automatic timer.

In the drawings similar numerals refer to similar parts throughout the several views.

The incinerator furnace of this invention is generally illustrated in FIGURE 1 and has a charging hopper 1 and a feed chute 2 which is relatively high to permit the accumulation of the material therein to such a degree as to avoid a back draft up the chute while the hopper is being substantially continuously charged. Should this continuous charging be interrupted, a covering as shown, should be placed over the hopper to prevent creating a natural draft so that the material would not catch fire in the chute. The material in chute 2 passes to grate 3 and the grates 3, 4, and 5 are of identical construction, like those shown in detail in FIGURES 2 and 3 and they have between them drop-off or nose grate sections 6. Beneath each section or stage of the grate are ash collectors 7 leading to a common chute 8 entering the final ash disposal bins 9 which also receive the ash directly from the final burning grate 5 continuously and bins 9 have a guide 10 therein which may be thrown to direct the ash to a leg of the bin not then being emptied.

In the construction shown air is preferably admitted to the under surface of the burning grates 4 and 5 and to the drop-off sections 6 but air is not admitted to the grate section 3 under the feed chute 2, to avoid ignition of material thereon within the chute. The material is fed from the hopper of a depth regulated by the cover chute top wall 11 and as it flows from the hopper grate to the first burning grate 4 it turns over and is broken up. It is broken up from the packing imparted to it in the hopper 1 and chute 2, so that it fires readily as it passes down the burning grates 4 and 5. It is again turned over at the vertically stationary nose grate between grate sections 4 and 5 and this cascading over the drop-off sections breaks open any masses of the material theretofore unbroken.

The grate lifting cylinders 12 and 13 are mounted in pairs on the frame work 14 of the furnace structure and each section or stage of the grates has separate pairs of pistons and cylinders for their operation, each pair being of identical construction and when several units of the furnace are required for increased capacity, the drive units of adjacent units are preferably placed in a common aisle between the units for convenient separate manual operation should that be desired.

The pistons and cylinders forming hydraulic motors are made generally like those in the patent to Turner et al., No. 2,752,756, July 3, 1956. As shown in this patent the pistons are double ended and driven from each end with the cross-head connected at the center. The forward head 15 of the piston in the upper cylinder 12 is shown at 15. The cross-head 16 on the piston of the upper cylinder is connected to link 17 which in turn is connected by rocker-arms 18 to shaft 19 which extends across the grates of the stage illustrated in FIGURES 2 and 3. Shaft 19 through means of rocker-arms 20 is connected to pull rods 21 which in turn are connected to connecting bars 22 to which alternate grate bars 23 are connected. The lower cylinder cross-head 24 through similar link 25, rocker-arm 26, shaft 27, rocker-arms 28, pull rods 29 and connecting bars 30 operates the alternate grate bars 31, pushing them upwardly on the left hand movement of the piston as shown in FIGURE 2. When the pistons return to their normal rest position, the grates return to their normal rest posi-

tion. The alternate movement or sequence of the grates feeds the refuse from the base of the chute 2 to the first combustion stage 4 and then to the stage 5, each operation of the grates moving the refuse forward a definite increment. This movement not only moves the refuse forward but it agitates it, keeps it porous, well distributed and free burning. One operation for both groups of alternate grates is termed a cycle of grate operation. By controlling the rest time of the pistons between the cycles, the progress of the burning mass down the grates can be regulated.

Pumps 32 driven by motors 33 furnish the hydraulic power for the cylinders. A pressure line 34 is divided, one branch leading to central opening 35 of the valve of FIGURE 11, and the other branch has branches 36 leading to the control head 37 at the end of the cylinders of each stage as shown in FIGURE 12; likewise leading to this control head are branches 38 and 39 of control lines 40 and 41 leading from the intermediate side cavities, 42 and 43 of the solenoid four-way valve shown in FIGURE 11 and the valve itself 44 is normally centered by means of springs 45 at each end. Likewise at each end of the valve is a non-magnetic pin 46 and a laminated iron core 47 which is pulled centrally upon magnetization of the solenoid coil 48. There is a manual pin 49 likewise at each end, pressure upon which moves the valve 44 off center. Pressure from the pumps 32 through line 34 enters the center cavity 35 of the solenoid valve. The solenoid valve also has spaced exhaust passages 50 connected to line 51 leading through the spring loaded check valve 52 back to the exhaust line and the pump reservoir. When the valve 44 is centered the branch control lines, 38 and 39, then serving as exhaust lines from the control heads, are open through the solenoid valve to the exhaust 50 line 51 and valve 52. Each time the four-way solenoid valve is operated oil pressure is admitted to the control head 37 of the cylinders. This control head includes an on-off valve 53 operated by handle 54 which must be turned to the on position as shown in solid lines in FIGURE 7 to connect with control pressure lines 40 and 41, to permit the pressure from the control pressure lines to pass therethrough.

The main pressure line 34 through its branches 36 is connected to the bottom of each cylinder control head 37 where the oil pressure is admitted through passage 55 to the center cavity 56 of each of two spool type spring offset valves 57 as shown in FIGURE 6. The lower spool valve is shown in its normal rest position with the spring 58 extended. In this position as shown in FIGURE 6 the oil pressure goes through passage 59 for the lower valve and passage 60 for the upper spool valve, when that valve is in the reversed position from that illustrated in FIGURE 6, to the rear of the cylinders and pistons as above described, respectively, to the lower and upper cylinder as shown in this FIGURE 6; with the lower spool valve at rest pressure is admitted to the front of the lower cylinder 13. In this position the pressure on the front of the lower cylinder will lower the grates of the attached set down to their normal rest position. In FIGURE 2 they are up, just before being lowered since their control lower spool valve is thrown, ready to lower them.

Pressure oil from the main pressure line 34 is also ported past the main spool valves through the top of the control head 37 and enters the center cavity 61 of the on-off valve 53 as shown in FIGURE 7 through passage 62. Oil from control lines 38 and 39 passes through ports 63 and 64 in the on-off valve to the manual valve 65 operated by handle 66 and through ports 67 and 68 respectively in the manual valve, when in neutral position shown in FIGURES 5, 6 and 7.

Pressure oil from the main pressure line 34 through the central opening 56 in the control head 37 is admitted to the cylinders for their operation when the spool valves 57 are in their left hand position as shown for the upper valve in FIGURE 6. The pressure with the valve 57 in the position shown goes through circular passage 69 in the control

head and along passage 70 therein and through passage 71 between cylinders 12 and 13 as shown in FIGURES 6 and 8 to the rear of the cylinders. This passage 71 is connected to drive the upper piston 15 through a passageway in the rear cylinder head, there being a hollowed projection 72 on the rear cylinder heads to form this passageway into the right hand end of the cylinders as shown in FIGURE 2. The admission of the pressure to the right end of the cylinders as shown in this FIGURE 2 elevates the grate bars 31 as above described. A similar drive passage for the piston in the lower cylinder 13 is shown in FIGURE 6, from circular passage 73, angular passage 74 and longitudinal passage 75 between the cylinders 12 and 13 to the rear head of cylinder 13 where a similar passage in a hollowed projection of that head provides for the admission of pressure fluid to the rear of the piston in the lower cylinder 13 to raise the alternate set of grate bars 23, upon the admission of pressure fluid to the rear end of this piston.

Upon the activation of the solenoid coil 48 moving the four-way solenoid valve shown in FIGURE 11 passage 35 is connected to the control line 38 through movement of the valve 44 to the left as shown in FIGURE 11 and this admits pressure through line 38 through the on-off valve 53 passage 63 therein and the manual valve, passage 67 thereof, and through passage 76 in the control head 37 to the right side of that housing as shown in FIGURE 6 to the operating piston cavity 77 of the operating piston 78 and this pressure overcomes the spring 58 to move the spool valve 57 to the left similar to the position shown for the upper spool valve in this FIGURE 6, which in turn then passes pressure from the pressure lines 34 and 36 to the rear of the lower cylinder 13 to move its piston forward and thereby effect the raising of the set of grate bars 31 as shown in FIGURE 2.

Movement of the solenoid four-way valve 44 in the opposite direction passes pressure from the control line 39 through the passages 64 and 68 of the on-off valve and manual valve and passage 79 in the control head 37 to the operating piston cavity 80, upon the introduction of pressure therein the operating piston 81 is moved to the left as shown in FIGURE 6 which permits the application of pressure to the rear end of the piston 15 in upper cylinder 12 and the raising of the alternate set of grate bars 23.

Exhaust chambers 82, 83, 84 and 85 are located near the extremities of the respective spool valves 57 and the respective pairs of these exhaust chambers are connected by passages 86 to the vertical passage 87 leading to the branch exhaust line 88 of the main exhaust line 89, back to the pump reservoir.

Upon the return of the lower spool valve 57 to its right hand rest position the exhaust from the rear end of the cylinder 13 passes through passageway 73 in the control head housing 37 through passageways 84, 86 and 87 to the exhaust line 88. Each control line from the control head housing 37 is in turn used as an exhaust line through that control head back to the pump reservoir through the passages above described.

If for any reason power is cut off the control or if the hydraulic pumps should fail during operation the grates will immediately return to their normal rest positions because all valves are spring returned to their normal rest positions and the residual pressure in the exhaust line 51 is always held by the check valve 52 to an adequate pressure to serve this purpose. This same result applies if the electric current should fail for the operation of the four-way solenoid valve because it too is spring centered.

To produce the sequence operation of alternate sets of grates by the movement of the solenoid valve back and forth, a program timing device like that shown in FIGURE 12 may be utilized. It will be understood that as long as pressure remains in the respective control lines the respective set of grates will be elevated and when that pressure is removed the spring centered spool valves 57 will oper-

ate and cut off the pressure from the pressure lines and return the raised grates to their lowered fuel supporting position. They remain up with the maintenance of pressure on the control lines and that pressure must therefore be maintained the required length of time after raising them and pressure must be left off the alternate control line a sufficient period of time to allow the raised set of grates to lower. Electric energy to operate the solenoid four-way valve 44 at regular intervals as described above may be supplied through a set of cams. As shown in 10 FIGURE 13, the cams may all be assumed to be carried on a common shaft of synchronous motor 90 shown in FIGURE 12. As illustrated the cams make a complete revolution in twelve seconds or a quarter revolution in three seconds. The cams have a large diameter section 91 and a small diameter section 92. The first cam set 93 closes the contacts 1A and 1B shown in FIGURES 13 and 12 and thereby energizes the left hand coil as shown in FIGURE 12 and movement of valve 44 to the right caused by the energizing of the left hand coil passes pressure through the control lines to the upper cylinders. The current on this coil remains closed for three seconds which is the length of time required to raise one set of grate bars to progress the material thereover. Cam 93 then opens its circuit and circuits through the timer remain open for another three seconds to allow the grate bars of the raised set time to lower. After the lapse of these six seconds cam 94 by its larger diameter section closes the current through contacts 2A and 2B shown in FIGURES 13 and 12 and the second set of grate bars is raised during the passage of a period of three seconds and then through the passage of another period of three seconds allowed time to lower, thus alternately moving four-way valve 44 back and forth and if the synchronous motor 90 be maintained in operation, this alternate movement of the grate bars will continue in cycles of five per minute.

It is, however, generally desired not to have precisely alternate movements of the grate bars in this timed sequence but rather to vary the time of dwell between movements of the grate bars and for this purpose a repeat cycle timer is employed. One of these is available from the Wilson Company of Huntington, West Virginia, which is their Model No. 2 made in 1959 and it is diagrammatically illustrated at 95 in FIGURE 12 of the drawing. This unit forms a time controlled relay circuit and is in line with the circuit to drive the synchronous motor 90 of the program timer, causing it to stop and restart in accordance with the opening or closing of contacts in the relay of the repeat cycle timer. As shown in this timer 95, electric line L1 is connected to it and to the left hand side of the synchronous motor 90, or line L1 of the program timer. Line L2 passes to contact 2 then 4 of the timer 95 and then to the magnetically controlled arm at the upper right hand corner of this timer. When current is not flowing through the magnetic coil, not shown, the movable arm by spring tension is pulled against contact 3 of the relay, which in this application is not used. When the magnetic coil is energized, it causes the movable arm 4 of the relay to overcome the spring tension and make contact with contact 5 of the relay and this point is connected to contact 5 of the timer 95 and a line L2 is further connected to line L2 of the program timer. It will be seen that the repeat cycle timer 95 controls the time the synchronous motor 90 is operated, and consequently the time the cam carrying shafts run.

It is important that the alternate movement of the grates be maintained to assure proper operation and for that purpose each cycle of operation should be complete and for that purpose again, the rotating shaft of the synchronous motor 90 should start and stop at the same point should electric energy be interrupted to lines L1 and L2 and reconnected. To accomplish this purpose a third cam set 96, FIGURE 13, is provided with a relatively short time that current is cut from contacts 3A

and 3B as shown in FIGURES 13 and 12 but during that time these contacts are open and the synchronous motor 90 stops and the springs of the various valves return the grates to their rest position. The cam set 96 may be manually adjustable on its cam shaft to assure that the cam stops at the same point each time the program timer ceases to activate the coils of the four-way valve.

The number of cycles of operation to accomplish optimum furnace results is determined by the time relay contacts 4 to 5 of the repeat cycle timer 95 remain closed or are open. The time of the on cycle, as well as the time of the off cycle, is readily adjustable by the range switches indicated in FIGURE 12. The Wilson No. 2 repeat cycle timer has an off-on switch which allows current and voltage to be applied to the transformer indicated, and from its secondary windings with the resistor-capacitor circuit and tube type 0D3 provides the power supply of the circuit of the duo triode tube 12AU7. Each triode section of the 12AU7 has its plate and grid circuit capacitor coupled as indicated on the diagram, FIGURE 12. Varying the range switch setting of the off cycle and the vernier adjustment will vary the off cycle of the repeat cycle timer in steps from a minimum of 0 seconds to maximum of 1000 seconds. The on cycle is variable by setting its corresponding range switch and vernier. The setting of the on cycle and the off cycle controls through the grid to plate capacitance coupling the time current flows through its corresponding half of the tube 12AU7. The coil of the relay R is in the plate circuit of one triode section of the 12AU7. When current flows through this magnetic coil, contacts 4 to 5 are closed. When current is prevented from flowing the coil has no magnetic field and the contacts open.

By setting the range switch on cycle and its vernier of the repeat cycle timer to allow an on time of 30 seconds, will allow the program timer cam shaft to make 3 full revolutions, since it is over 24 seconds and under 36 seconds, and cause the cycles of grate operation.

By setting the range switch off cycle and its vernier 40 for an off time of 120 seconds, interrupts the current flow to the program timer for this amount of time, deactivating the grates for this period of time.

The cycle of operation will repeat until a readjustment of the range switches with their respective verniers, or 45 the off-on switch is turned to off.

There will be times when it is desirable, due to the character of the material to either prevent a stage of grates from operating for a short space of time or to activate the rates of a stage when the unit happens to be in the off cycle. The manual operating valve and on-off valves above described serve this purpose best. In FIGURES 5 and 7 the on-off valve is shown open or on. Should this valve be rotated clockwise as shown by the dotted line position of the handle in FIGURES 4 and 7, ports 63 and 64 will be closed, so will the passage of oil from cavity 61 be cut off. Should either piston of the cylinders be in process of raising the grates at this time, oil pressure in any of the ports is exhausted through port 97 extending the length of the on-off valve and it drains through the end of that housing through passageways 98 and 99 to the exhaust valve cavity 83, particularly as shown in FIGURE 6. The cavity 100 likewise drains oil from the housing of the manual valve 65 to that of the on-off valve 53. While the on-off valve is in its closed position above described no operation of the pistons in either direction either manually or by means of the solenoid four-way valve can take place until this on-off valve is first opened by counterclockwise rotation to its original on position. With this on-off valve in its on position but with the repeat cycle timer in the off position, operation of any cylinder may be accomplished by the oil pressure from the main pressure line in the central cavity 101 being received from the center cavity 61 of the on-off valve. This pressure through cavity 101 is ineffective when the manual valve is in neutral position as shown in

FIGURES 5, 6 and 7. When the handle 66 of this valve is turned to the left as shown in FIGURES 4, 5 and 7, oil flows from the center cavity 101 of the valve through the off-set port 102 to passage 76 and the operating piston cavity 77, moving the operating piston 78 and then the lower spool valve 57 and the lower piston in cylinder 13. When the handle 66 is moved to the right as shown in FIGURES 4, 5 and 7, oil passes from the central cavity 101 to the off-set port 103 through passage 79 to piston cavity 80 causing the upper piston 15 in cylinder 12 to be operated. Returning the manually operated valve to neutral again blocks off these valve ports 102 and 103 of oil supply from the pressure line and connects the ports 67 and 68 for automatic operation by the four-way solenoid valve.

The ability to operate manually without interference with the automatic controls and without the necessity of adjustment before and/or after manual operation enables the operator to take immediate action at the desired locations of the equipment without the necessity of upsetting the worked out automatic control setting.

What is claimed as new and is desired to be secured by letters patent is:

1. A furnace for burning refuse comprising a plurality of tandem sets of alternately actuated stoker bars which in normal position form a forwardly and downwardly inclined supporting surface for the refuse, downwardly inclined supporting means for said bars, a furnace frame on which said supporting means are mounted, said bars being movably mounted so that they can be tilted forwardly to advance the refuse and then retracted and means including reciprocating bars connecting the alternate bars of each set together to be so moved together, individual hydraulic motors mounted on said frame and connected to each set of said reciprocating bars to operate the same, a source of fluid pressure connected by conduit lines to each motor, manually controlled means to operate each motor independently of the others from said source, separate pressure control conduit lines leading from said source to each motor, means in said control conduit lines to connect the motors of the separate sets of bars to the pressure conduit line to pass pressure simultaneously through the pressure and control conduit lines for repeated predetermined periods of time to raise the bars to material forwarding position and means to lower all the bars to material supporting position upon failure of fluid pressure from said source, means to cut off the connection of the control conduit lines to the motors upon operation of the manually controlled means.

2. A furnace for burning refuse comprising a plurality of tandem sets of alternately actuated stoker bars which in normal position form a forwardly and downwardly inclined supporting surface for the refuse, downwardly inclined supporting means for said bars, a furnace frame on which said supporting means are mounted, said bars being movably mounted so that they can be tilted forwardly to advance the refuse and then retracted and means including reciprocating bars connecting the alternate bars of each set together to be so moved together, individual hydraulic motors mounted on said frame and connected to each set of said reciprocating bars to operate the same, a source of fluid pressure, a double ended hydraulic motor connected to each reciprocating bar, to raise and lower the respective sets of stoker bars upon admission of fluid to the respective ends of the motors, conduit lines connecting the source to each motor, adjustable automatic means connected by conduit lines from said source to said motors to admit the fluid to the respective motors of each set in a predetermined sequence and for predetermined periods of time for both motor activation and motor rest, manually controlled means within the pressure conduit lines between the source and motors to admit the fluid to the respective ends of the motors, means connected with the manually controlled means to make ineffective the operation of the automatic means without

disturbing the adjustment for the predetermined periods thereof.

3. A furnace for burning refuse comprising a plurality of tandem sets of alternately actuated stoker bars which in normal position form a forwardly and downwardly inclined supporting surface for the refuse, downwardly inclined supporting means for said bars, a furnace frame on which said supporting means are mounted, said bars being movably mounted so that they can be tilted forwardly to advance the refuse and then retracted and means including reciprocating bars connecting the alternate bars of each set together to be so moved together, individual hydraulic motors mounted on said frame and connected to each set of said reciprocating bars to operate the same, a source of fluid pressure, a double ended hydraulic motor connected to each reciprocating bar, to raise and lower the respective sets of stoker bars upon admission of fluid to the respective ends of the motors, conduit lines connecting the source to each motor, a spring set sliding valve and housing therefor adjacent each motor, the housings and motors having passages therein connecting the valves of the respective motors to said source, each said valve when set by its spring admitting fluid from the source to its respective motor to return the stoker bars to material supporting position, and means to repeatedly move the valve to pressure stoker bar raising position for predetermined intervals and at predetermined times.

4. A furnace for burning refuse comprising a plurality of tandem sets of alternately actuated stoker bars which in normal position form a forwardly and downwardly inclined supporting surface for the refuse, downwardly inclined supporting means for said bars, a furnace frame on which said supporting means are mounted, said bars being movably mounted so that they can be tilted forwardly to advance the refuse and then retracted and means including reciprocating bars connecting the alternate bars of each set together to be so moved together, individual hydraulic motors mounted on said frame and connected in pairs to each set of said reciprocating bars to operate the same, a source of fluid pressure, conduit lines connecting the source to each pair of motors, a control head having normally closed valves therein on each pair of motors, electrically actuated hydraulic control means connected by additional conduit lines between said source and each control head to open said valves to admit pressure from said source through said first named conduit lines and to the respective motors of each set for repeated predetermined periods of time for both motor activation and motor rest, said last named means including means to restore the stoker bars to supporting position upon failure of electric current thereto.

5. A furnace for burning refuse comprising a plurality of tandem forwardly and downwardly inclined stages of sets of alternately actuated stoker bars, downwardly inclined supporting means for said bars, a furnace frame on which said supporting means are mounted, the stages being vertically substantially spaced to cause refuse from the upper stage to disintegrate in falling to the bars of the adjacent lower stage, individual hydraulic motors mounted on said frame and connected to the alternate sets of bars of each stage to operate the same, a common source of fluid pressure for said motors, conduit lines connecting the source to each motor, normally closed valves on each motor in said conduit lines, to control the pressure to the motors, common hydraulic actuating means connected by additional conduit lines from said source to said valves, to open the same to admit the pressure from said source through said first named conduit lines to said motors of each set with a predetermined sequence for repeated predetermined periods of time, pressure control means in said additional conduit lines to restore the bars of all the sets to refuse supporting position upon failure of the common actuating means.
